UNITED STATES PATENT OFFICE.

FRANK GMEINWIESER, OF ROCHESTER, NEW YORK.

CLOTHESRACK.

Application filed July 24, 1922. Serial No. 577,624.

To all whom it may concern:

Be it known that I, FRANK GMEINWIESER, a citizen of the United States, residing at Rochester, in the county of Monroe and 5 State of New York, have invented certain new and useful Improvements in Clothes-racks, of which the following is a specification.

The object of this invention is to provide an improved form of clothes rack which is made durable in construction and on which the clothes bars can be quickly and readily placed into a vertical or horizontal position.

15 Another object of this invention is to construct this clothes rack so that the clothes bars can be detached from the bracket when it is desired or necessary to do so.

These and other objects of this invention 20 will be fully illustrated in the drawing, described in the specification and pointed out in the claims at the end thereof.

In the accompanying drawing:

Figure 1 is a top plan view of the clothes 25 rack.

Figure 2 is a vertical sectional view of the clothes rack with the section taken on the line 2^x—2^x of Figure 1.

Figure 3 is a detail view of the bracket on 30 which the clothes bars are supported.

In the several figures of the drawing, like reference numerals indicate like parts.

A clothes rack with adjustable bars supported thereon is used in kitchens, bath 35 rooms, etc. for the purpose of providing means on which clothes, towels, etc. can be suspended to dry. The bars of such a clothes rack are made adjustable so that they can be moved out of the way when the clothes 40 rack is not in use. Therefore, the bars are held supported in either a horizontal position in which position the clothes can be placed thereon, or the bars are placed in a vertical position parallel to the wall on 45 which the bracket is supported so as not to project into the room when the bars are not needed.

Clothes racks of this type have heretofore 50 been constructed entirely of wood or the bracket has been made of iron and the bars of wood. However, either of these constructions are limited in their supporting capacity in that the wooden bars easily break when taxed to their capacity. In 55 my present invention I have endeavored to construct a clothes rack of which all of

the parts are either made of iron or steel in order to provide a rack that will last indefinitely under ordinary usage.

As illustrated in the accompanying drawing this clothes rack is made up of the bracket 1 with which the clothes rack is fastened to the wall or other suitable support therefor. This bracket comprise a vertical plate having the supporting flanges 2 and 3 60 bent out at right angles therefrom. In the plane 1 are drilled the holes 4 through which screws 5 are adapted to pass to fasten the bracket rigidly to its support. Mounted between the flanges 2 and 3 are the cross bars 6 65 and 7. These cross bars are threaded at their ends with a female thread so that a cap screw 8 can be threaded into it to fasten and support these cross bars at each end thereof to the flanges 2 and 3 respectively. 70

Supported from the bracket 1 and its cross bars 6 and 7 is the segmental bracket 9. This bracket has a pair of rearwardly extending locking flanges 10 and 11 formed thereon. These locking flanges are located 75 at the rear of the segmental bracket 9 in the middle thereof and are spaced to project between the flanges 2 and 3 of the bracket 1. Each of the locking flanges has a vertical slot 12 formed near the outer 80

free end thereof and a partly vertical and horizontal or T shaped slot 13 near the inner end thereof. The slot 12 of these locking flanges is open at the top of the flange and the vertical section 13^a of the slot 13 is 85 open at the bottom of the flanges. As illustrated in Figure 1 and 2 the cross bars 6 and 7 are adapted to engage into the slots 12 and 13 respectively in such a manner that will make the locking flanges 10 and 90 11 rest on top of the cross bar 7 while the under side of the end of these flanges engage the cross bar 6 of the bracket 1. This engagement of the locking flanges 10 and 11 with the cross bars 6 and 7 supports the 95 segmental bracket 9 in a horizontal position on the bracket 1.

In this position the clothes bars 14 project 100 out horizontally from the bracket 1 ready to receive the clothes to be suspended therefrom. For the purpose of strengthening the bars and preventing their breaking off from the segmental bracket 9, each of the bars 14 has a bend 15 formed on the inner end thereof. The free end of this bend is threaded 110 and passes through a hole in the segmental bracket 9 and has the locknuts 16 and 17

threaded thereon on top and one at the bottom of the bracket 1. Each of the bars is thus securely held in place on the bracket but allowed to swing thereon. In this way 5 the bars 14 can be made to project radially from the segmental bracket 9 to increase the free space between them. The bend 15 allows the bars to yield so that the bars can give when being overloaded where otherwise 10 these bars might break or at least bend badly.

As illustrated in dotted lines in Figure 2, the arrangement of the slots in the locking flanges 10 and 11, with relation to the position 15 of the cross bars 6 and 7 on the bracket 1, is such that these locking flanges can be disengaged from either one or both of the cross bars 6 and 7. The dotted line position of these parts in Figure 2 shows the flanges 20 10 and 11 and its associated parts in a vertical position and supported from the cross bar 7. In order to place the bars into this position they first have to be lifted from the horizontal position until the cross bar 6 has 25 been disengaged from the slot 12 in the locking flanges. When this is done these flanges are pulled away from the cross bar 6 until the cross bar 7 has travelled the full length of the slot 13. At this point the outer ends 30 of the locking flanges 10 and 11 have been moved clear of the cross bar 6 and are located in front of it. The flanges are then free to rock on the cross bar 7 as a center and move from the full line position to the 35 dotted line position as illustrated in Figure 2.

When it is desired to completely disengage the bars from the bracket 1, the bars with the segmental bracket 9 and locking 40 flanges 10 and 11 are lifted until the bar 7 is located opposite the openings 13^A of the slot 13 after which the flanges 10 and 11 can be moved sideways to disengage the cross bar from the slot 13 through this opening.

45 I claim:

1. In a clothes rack, the combination of a bracket, a pair of flanges projecting out from said bracket, a pair of cross bars mounted between said flanges, a segmental 50 bracket, a pair of locking flanges projecting rearwardly of said segmental bracket, said locking flanges having a pair of slots formed therein one at the top and one at the bottom of each of said locking flanges, said cross 55 bars being adapted to engage into the slots in said locking flanges and support said segmental bracket horizontally on the cross bars clothes bars supported by said segmental rack.

60 2. In a clothes rack, the combination of a

bracket, a pair of flanges projecting out from said bracket, a pair of cross bars mounted between said flanges, a segmental bracket, a pair of locking flanges projecting rearwardly of said segmental bracket, said locking flanges having a pair of slots formed therein, one at the top and one at the bottom of each of said locking flanges, said cross bars being adapted to engage into the slots in said locking flanges and support said segmental bracket horizontally on the cross bars, one of the slots in said locking flanges being elongated horizontally to permit said flanges to move endwise on the cross bar engaging into the elongated slot in order to 70 disengage the locking flanges from the other of said cross bars clothes bars supported by said segmental rack.

3. In a clothes rack, the combination of a bracket, a pair of flanges projecting out from 80 said bracket, a pair of cross bars mounted between said flanges, a segmental bracket, a pair of locking flanges projecting rearwardly of said segmental bracket, said locking flanges having a pair of slots formed 85 therein one at the top and one at the bottom of each of said locking flanges, said cross bars being adapted to engage into the slots in said locking flanges and support said segmental bracket horizontally on the cross 90 bars, one of the slots in said locking flanges being elongated horizontally to permit said flanges to move endwise on the cross bar engaging into the elongated slot in order to 95 disengage the locking flanges from the other of said cross bars, a series of bars mounted 100 to swing in said segmental bracket, each of said bars having a rectangular bend and curve on the inner end thereof to make it springy at the point of attachment to said segmental bracket.

4. In a clothes rack, the combination of a bracket, a pair of flanges projecting out from said bracket, a pair of cross bars mounted between said flanges, a bracket, a 105 pair of locking and supporting flanges projecting rearwardly of said bracket, said locking and supporting flanges having a vertical and a horizontal slot formed therein, one of said cross bars being adapted to 110 engage into the horizontal slots to form a fulcrum on which said bracket can swing, the other of said cross bars adapted to engage the vertical slots in said locking and supporting flanges to hold said bracket 115 against endwise movement and against rocking on the first of said cross bars, clothes bars carried on said bracket.

In testimony whereof I affix my signature.
FRANK GMEINWIESER.
